Claims priority, application Great Britain, Jan. 3, 1962, 285/62

4 Claims. (Cl. 139—58)

This invention relates to dobby mechanisms for looms. It is well known that in the weaving of fabrics the warp threads are passed through healds of a loom which are periodically raised and lowered horizontally to divide or shed the warp threads, so that the shuttle can carry the weft threads between the warp threads.

Dobby mechanisms are used in looms intended to weave relatively complicated patterns to control the shedding of the warp threads in a sequence determined by a desired pattern of weaving.

It is an object of the invention to provide an improved dobby mechanism which is capable of operating at much higher speeds than known mechanisms and which will positively control the motion of heald frames containing the healds of the loom.

According to the present invention, there is provided a dobby mechanism comprising a plurality of frame shafts arranged in a row, each frame shaft being pivotally connected to a heald frame and being vertically movable to raise and lower the frame; a pair of pivotally mounted shedding arms arranged one on each side of the row of frame shafts and capable of independently swinging up and down about their pivots to raise and lower the frame shafts; control means operable to swing the frame shafts about their pivotal connections with the heald frames from a neutral position into engagement with either one of the shedding arms in a sequence determined by a desired weaving pattern; and stop means for retaining the frame shafts, when they are disengaged from the shedding arms, in either the fully raised or the fully lowered position under the control of the control means.

The control means can be an arrangement of cams or chains or it can be electric or electronic device capable of swinging the drive members in a determined sequence.

The invention is particularly advantageous in its application to looms for weaving narrow fabrics, but is also applicable to looms for wide fabrics.

A preferred embodiment of the invention is illustrated in the accompanying drawing which is a perspective view of a dobby mechanism for a narrow fabric loom.

The mechanism illustrated is arranged in a housing 1 and comprises a plurality of vertically disposed frame shafts 2 only one of which is shown in the drawing for reasons of clarity. These frame shafts 2 are conveniently metal strips arranged in a row with their faces presented to one another. A heald frame 3 is connected at a pivot 4 to the top of each frame shaft 2, preferably in a way which permits the frame 3 to be detached if desired.

A pair of horizontal drive levers or shedding arms 5 is arranged with one arm on each side of the row of frame shafts 2. These arms 5 are mounted on pivots 6, or on a common pivot, at one end so that the arms can be swung up and down independently of one another. The end portions of the arms 5 remote from the pivots 6 are movable in shedding arm guides 7 secured to one wall of the housing 1. Two eccentrics 8 are mounted on a horizontal drive shaft 9, are each connected by a connecting rod 10 with one of the shedding arms 5 and are rotatable to raise and lower the arms 5 about their pivots 6 and consequently to raise and lower the heald frame 3. If desired, the connecting rods 10 and the eccentrics 8 can

2

be made adjustable to allow the permitted vertical movement of the shedding arms 5, and therefore heald frames 3, to be adjusted.

Each of the frame shafts 2 has a constricted waist portion 11 intermediate its ends to provide recesses at opposite edges of the shafts 2. Each of these recesses can engage the adjacent shedding arm 5 to enable its frame shaft to be raised or lowered. The frame shafts 2 normally occupy a neutral position in which their recesses are disengaged from both shedding arms 5, but they can be engaged with, or disengaged from, either of the levers 5 in sequence by a control means now to be described.

This control means includes a plurality of control rods 12 each of which is associated with one of the frame shafts 2, only one control rod being illustrated in the drawing. Each control rod 12 has a pin-and-slot connection 13 with its associated frame shaft 2 below the constricted waist portion 11. Each control is connected to, and is movable with, one end of a slide or push-rod 14 having a cam follower roller 15 at the other end, the roller 15 being in engagement with the edge of a cam disc 16; alternatively the disc 16 can be replaced by other cam means such as a chain. Each push-rod 14 is loaded by a spring 17 for movement in one direction and is pushed in the opposite direction by the cam 16. Thus, the frame shafts 2 can be engaged with either one of the shedding arms 5 or can be made to occupy the neutral position when it is disengaged from both arms 5, the sequence of movement being determined by the cams 16 which are selected in accordance with a desired weaving pattern. The cams 16 are arranged as a unit on a cam shaft 18 mounted on a support bracket 19 of the housing 1 and can be replaced by another unit when it is desired to weave another pattern. The cam shaft 18 is rotated by the drive shaft 9 through a worm 20 and worm wheel 21.

It will be appreciated that the movements of the control rods could be determined by electric or electronic means if desired.

It is necessary for the frame shafts 2 to be retained periodically in either the fully raised or fully lowered positions. For this purpose the lower end of each shaft 2 is vertically movable in a vertical slot 22 in a stop gate 23. Horizontal slots 24, 25 lead out of this vertical slot 22 in positions respectively corresponding to the upper, lower limits of movement of shaft 2 and its heald frame 3 and form abutments in which a projection 26 on the shaft 2 can engage when it is at the top and bottom of its stroke. The shaft 2 will then dwell at the top or bottom of its stroke until urged by the control means into engagement with one of the shedding arms 5.

We claim:

1. A dobby mechanism comprising a plurality of frame shafts and heald frames arranged in a row, each frame shaft being pivotally connected to a heald frame and being vertically movable to raise and lower the frame; a pair of pivotally mounted shedding arms arranged one on each side of the row of frame shafts and capable of independently swinging up and down about their pivots to raise and lower the frame shafts; control means operable to swing the frame shafts about their pivotal connections with the heald frames from a neutral position in which they are disengaged from both shedding arms into engagement with either one of the shedding arms in a sequence determined by a desired weaving pattern; and stop means for retaining the frame shafts, when they are disengaged from the shedding arms, in either the fully raised or the fully lowered position under the control of the control means.

2. A mechanism as claimed in claim 1 wherein the control means comprises a plurality of control rods each

of which is connected with one of the frame shafts, spring-loaded push rods connected through said control rods with the frame shafts and provided with cam follower rollers, a rotatable cam shaft mounted adjacent to said rollers, and cams mounted on said cam shaft and rotatable therewith to displace the control rods thereby to engage the frame shafts with, or disengage them from, either one of the shedding arms.

3. A mechanism as described in claim 1 including driving means for said shedding arms comprising a rotatable shaft, eccentrics mounted on said shaft, and adjustable connecting rods operatively connecting each shedding arm to a respective eccentric. 10

4. A mechanism as described in claim 1, said stop means comprising a fixed stop gate having a vertical slot therein for each frame shaft and two horizontal slots leading from each said vertical slot, and a projection on each frame shaft arranged to enter one or the other of 15

said horizontal slots when the frame shaft is moved to its neutral position at the top or bottom of its stroke.
